(57) **CLAIM**

The ornamental design for a clip for attaching heatsinks, as shown and described.

DESCRIPTION

FIG. 1 is a right front perspective view of an embodiment of the clip for attaching heatsinks, showing the lever arm in an open position.

FIG. 2 is a rear elevation of the embodiment of FIG. 1.

FIG. 3 is a bottom plan of the embodiment of FIG. 1.

FIG. 4 is a left side elevation of the embodiment of FIG. 1. FIG. 5 is a right front perspective showing the embodiment of FIG. 1 with its lever arm in a closed position, and a representative heatsink; and,

FIG. 6 is a front elevation of the embodiment and the heatsink shown in FIG. 5.

The components shown in phantom in FIGS. 5 and 6 do not form a part of the present invention.
